Patented Feb. 28, 1922.

UNITED STATES PATENT OFFICE.

WILLIAM WILLIAMS, OF DUGGER, INDIANA.

CLOSURE FASTENER.

1,408,236.

Specification of Letters Patent. Patented Feb. 28, 1922.

Application filed May 9, 1921. Serial No. 467,872.

To all whom it may concern:

Be it known that I, WILLIAM WILLIAMS, a citizen of the United States, residing at Dugger, in the county of Sullivan and State 5 of Indiana, have invented certain new and useful Improvements in Closure Fasteners, of which the following is a specification.

This invention relates to devices applicable to swinging doors for the purpose of holding the same in open or partly open position, and its object is to provide a device which is very simple and efficient, and which can be readily operated to hold the door in any desired position, and to release 10 the door, so that it may be closed.

The object stated is attained by means of a novel combination and arrangement of parts to be hereinafter described and claimed, and in order that the same may be 20 better understood, reference is had to the accompanying drawing forming a part of this specification.

In the drawing Fig. 1 is an elevation of 25 the device showing its application; Fig. 2 is a plan view showing the door swung partly open; Fig. 3 is a view similar to Fig. 2 but showing the parts in another position, and Fig. 4 is an enlarged cross section on the line 4—4 of Fig. 3.

Referring specifically to the drawing, 30 5 denotes a fragment of a swinging door to which the invention is applied. The top 6 of the door frame carries a bracket member having an outstanding horizontal flange 7 which is provided with a longitudinal slot 8, one edge of which latter is notched as 35 shown at 9. The flange 7 forms the keeper member of a locking pin 10 carried by the forward end of a yoke 11 which straddles the 40 flange. The pin 10 seats slidably in the slot 8 and is adapted to be shifted laterally to enter one of the notches 9, the yoke being sufficiently loose to permit this movement of the pin.

45 The face of the door 5 carries, near the top, a bracket 12 having an upturned pin 13 which pivotally supports a socketed member 14. To the member 14 is connected one end of a rod 15 which has its other end 50 connected to the rear end of the yoke 11, whereby a connection between the door 5 and the yoke is had. The pivot pin 13 is laterally spaced from the flange 7, and the connection 15 is arranged to locate the yoke 55 11 obliquely with respect to the flange, so

that it may slide freely along the same when the door 5 is swung open or closed. The rod 15 is screwed into the member 14 so that its effective length may be varied for the purpose of properly adjusting the 60 parts. The rod 15 is also shown as being screwed into the rear end of the yoke and fitted with a nut 16 back of the latter. It is to be understood however, that the parts may be held in assembled relation in any 65 other suitable manner.

On top of the flange 7 seats a shifter bar 17 for the pin 10, to take the same into and out of the notches 9. This bar has longitudinal slot 18 parallel to the slot 8 and at its 70 ends are oblique slots 19 into which extend stationary pins 20 carried by the flange 7. It will therefore be seen that a movement of the bar 17 in the direction of its length is accompanied by a transverse movement, 75 and as the pin 10 also extends through the slot 18, the lateral movement of the bar operates to carry said pin into and out of the notches 9.

Any suitable means may be provided for 80 operating the shifter bar 17. The drawing shows one end of the bar linked to a bell crank lever 21 carried by the side 22 of the door frame, and connected by a link 23 to an operating lever 24, which latter is also carried by said side of the door frame.

The shifter bar 17 is normally so positioned on the flange 7 that it covers the notches 9 as shown in Fig. 2, and the door 5 may now be swung as the pin 10 is held 90 free of the notches so that it may slide in the slots 8 and 18. To lock the door in the partly open position shown in Fig. 2, the hand lever 24 is operated to slide the shifter bar 17 to the right from the position shown, 95 so that it assumes the position shown in Fig. 3. This movement of the bar, through the pin 20 and the oblique slots 19, was accompanied by a forward or lateral movement of the bar to the position shown in 100 Fig. 3, resulting in the pin 10 being forced over into one of the notches 9. The door is now securely locked in partly open position, and before it can be closed, the bar 17 must be moved back to the position shown in Fig. 105 2, by which the pin 10 is carried rearwardly out of the notch in which it had been previously seated. In this manner the door can be swung open to any desired degree, and it will be securely held in such position, and 110

at the same time, its release to permit closing is readily effected, the hand lever 24 being located so as to be within easy reach.

The preferred embodiment of the invention has been illustrated, but it will be understood that many changes and modifications may be made without a departure from the spirit and scope thereof as claimed hereinafter. The invention is also readily applicable to other swinging closures besides doors.

I claim:

1. The combination with a swinging closure, of a keeper member having a longitudinal slot one edge of which is notched, a pin slidably seating in the slot and movable laterally to engage the notched edge thereof, a support for the pin slidable along the keeper member, an operative connection between said member and the closure, a shifter bar for the pin having a slot in which the pin slidably seats, and which slot is parallel to the slot of the locking member, and means for moving said bar laterally to force the pin into and out of locking engagement with the notched edge of the keeper member slot.

2. The combination with a swinging closure, of a keeper member having a longitudinal slot one edge of which is notched, a pin slidably seating in the slot and movable laterally to engage the notched edge thereof, a support for the pin slidable along the keeper member, an operative connection between said member and the closure, a shifter bar for the pin having a slot in which the pin seats, and which slot is parallel to the slot of the locking member, said bar being slidably longitudinally on the keeper member, and means for imparting to said bar a lateral movement when it is slid to force the pin into and out of locking engagement with the notched edge of the keeper member slot.

3. The combination with a swinging closure, of a keeper member having a longitudinal slot one edge of which is notched, a pin slidably seating in the slot and movable laterally to engage the notched edge thereof, a support for the pin slidable along the keeper member, an operative connection between said member and the closure, a shifter bar for the pin having a slot in which the pin seats, and which slot is parallel to the slot of the locking member, said bar being slidably longitudinally on the keeper member, and means for imparting to said bar a lateral movement when it is slid to force the pin into and out of locking engagement with the notched edge of the keeper member slot, said means being oblique slots in the bar and rigid pins on the keeper member extending into said slots.

4. The combination with a swinging closure, of a keeper member having a longitudinal slot one edge of which is notched, a 65 yoke straddling said member, a pin carried by the yoke, said pin slidably seating in the aforesaid slot and being movable laterally therein to engage the notched edge thereof, a rod connecting the yoke with the closure, 70 said rod having a pivotal connection with the closure, a shifter bar seating slidably on the keeper member and having a slot into which the aforesaid pin slidably extends, and which slot is parallel to the slot of the keeper 75 member, and means for moving said bar laterally to force the pin into locking engagement with the notched edge of the keeper member slot.

5. The combination with a swinging closure, of a keeper member having a longitudinal slot one edge of which is notched, a yoke straddling said member, a pin carried by the yoke, said pin slidably seating in the aforesaid slot and being movable laterally 85 therein to engage the notched edge thereof, a rod connecting the yoke with the closure, said rod having a pivotal connection with the closure, a shifter bar mounted on the keeper member for a longitudinal sliding 90 movement thereon, said bar having a slot into which the aforesaid pin extends, and which slot is parallel to the slot of the keeper member, means for sliding the bar, and means for imparting to the bar a lateral 95 movement accompanying its sliding movement to force the pin into and out of engagement with the notched edge of the keeper member slot.

6. The combination with a swinging closure, of a keeper member having a longitudinal slot one edge of which is notched, a yoke straddling said member, a pin carried by the yoke, said pin slidably seating in the aforesaid slot and being movable laterally 100 therein to engage the notched edge thereof, a rod connecting the yoke with the closure, said rod having a pivotal connection with the closure, a shifter bar mounted on the keeper member for a longitudinal sliding 105 movement thereon, said bar having a slot into which the aforesaid pin extends, and which slot is parallel to the slot of the keeper member, means for sliding the bar, and means for imparting to the bar a lateral 110 movement accompanying its sliding movement to force the pin into and out of engagement with the notched edge of the keeper member slot, said last-mentioned means being stationary pins on the keeper member 115 and oblique slots in the bar into which said pins extend.

In testimony whereof I affix my signature.
WILLIAM WILLIAMS.
